UNITED STATES PATENT OFFICE.

WILLIAM B. TERRY, OF NEW YORK, N. Y., ASSIGNOR TO JULIUS KAYSER & CO., OF NEW YORK, N. Y., A CORPORATION OF NEW YORK.

DESIGN FOR RIBBON.

Application filed October 4, 1924. Serial No. 10,968. Term of patent 7 years.

To all whom it may concern:

Be it known that I, WILLIAM B. TERRY, a citizen of the United States of America, residing at New York, in the county and State of New York, have invented a new, original, and ornamental Design for Ribbon, of which the following is a specification, reference being had to the accompanying drawing, forming part thereof.

The drawing is a plan view of the front face of the ribbon.

I claim:

The ornamental design for ribbon, as shown.

WILLIAM B. TERRY.
